UNITED STATES PATENT OFFICE.

JOHN I. WEISNEK, OF SHERIDAN, WYOMING, ASSIGNEE OF ONE-HALF TO HARRY H. EVANS, OF SHERIDAN, WYOMING.

WRENCH.

1,164,149.

Specification of Letters Patent. Patented Dec. 14, 1915.

Application filed June 12, 1915. Serial No. 33,735.

To all whom it may concern:

Be it known that I, JOHN I. WEISNEK, a citizen of the United States, residing at Sheridan, in the county of Sheridan and 5 State of Wyoming, have invented certain new and useful Improvements in Wrenches, of which the following is a specification.

My invention relates to improvements in wrenches, and my object is to provide a 10 new and useful device of this character wherein instant adjustment of the wrench jaws may be had for gripping a nut or other device to be turned with the wrench.

The invention further embraces means for 15 causing the jaws to firmly grip a nut or other object after they have been quickly adjusted into engagement therewith.

Other objects of the invention will herein-after appear, and in order that said invention may be fully understood, reference will 20 now be made to the accompanying drawing, in which:

Figure 1 is a side elevation of a wrench embodying my invention. Fig. 2 is a side 25 elevation of the wrench with a portion thereof in vertical section. Fig. 3 is a vertical cross section on line III—III of Fig. 1. Fig. 4 is a detail isometric view of a worm and a holder therefor, constituting important features of the invention. Fig. 5 is a 30 broken horizontal section on line V—V of Fig. 1, with the worm and its holder removed.

In carrying out the invention, I employ 35 a toothed-bar 1, provided at one end with a handle 2, and at its opposite end with a fixed jaw 3. The toothed-bar 1 also is provided at one side with a longitudinal guideway 4, for a purpose which will here- 40 after appear.

5 designates a movable jaw integral with a sleeve 6 slidably mounted upon the toothed-bar 1, so that the movable jaw may be adjusted toward or away from the fixed jaw 3. 45 The sleeve 6 is loosely mounted upon the toothed-bar 1, so that it may be quickly slid in either direction thereon, but in order

that there may not be undue lateral play between said toothed-bar 1 and the sleeve 6, I provide the latter with integral lugs 7 50 which snugly fit within the guideway 4, but are free to move longitudinally therein.

8 designates a holder, preferably, in the form of a yoke surmounted by a thumb-piece 9 and a pair of depending arms 10, 55 which latter have vertical movement in vertical grooves 11 in the sleeve 6. The arms 10 have slots 12 for the passage of the toothed-bar 1, and the thumb-piece 9 has a recess 13 to receive the upper portion of a coil spring 60 14 bearing down upon the top of the sleeve 6, see Figs. 2 and 3.

15 designates a gear, preferably, in the form of a worm journaled in the lower ends of the arms 10 and adapted to intermesh 65 with the teeth of the bar 1.

When a nut or other device is to be gripped, the wrench is placed in position thereon with the inner wall of the fixed jaw 3 and the underside of the toothed-bar 1 70 engaging said device. Pressure is then applied to the thumb-piece 9 to overcome the resistance of the spring 14 and depress the yoke 8 until the gear 15 clears the teeth of the bar 1, as disclosed by Fig. 2. The sleeve 75 is then adjusted forward until the movable jaw 5 engages the opposite side of the device from that engaged by the fixed jaw 3. The spring 14 is then permitted to raise the yoke 8 and thrust the gear 15 into engagement with the rack teeth, when further adjustment of the jaw 5 may be had, if desired, to firmly grip the device. If desired the periphery of the worm teeth may be notched or knurled, so that a firmer grip 85 may be had on said worm when rotating the same.

While I have shown and described the preferred form of my invention, I reserve the right to make such changes in the construction, arrangement and proportion of parts as properly fall within the spirit and scope of the claim.

Having thus described my invention, what

I claim and desire to secure by Letters Patent, is:

In combination with the rack bar of a wrench, a sleeve slidable thereon and having two pairs of transverse grooves disposed one pair on each side of the sleeve, a worm carrier composed of a yoke having apertures to receive the bar, said yoke having its sides of a thickness so as to be received

in said transverse grooves of the sleeve, and 10 a coil spring seated on the sleeve and engaged with the top of the yoke.

In testimony whereof I affix my signature, in the presence of two witnesses.

JOHN I. WEISNEK.

Witnesses:

S. H. JOHNSON,
J. D. GILLESPIE.
